UNITED STATES PATENT OFFICE.

EDWARD I. KRAMER, OF NEW YORK, N. Y.

DEVICE FOR COMPUTING THE COST OF ENGRAVINGS.

1,158,508.

Specification of Letters Patent.

Patented Nov. 2, 1915.

Application filed December 29, 1914. Serial No. 879,508.

To all whom it may concern:

Be it known that I, EDWARD I. KRAMER, a citizen of the United States, residing at New York, in the county of New York and State 5 of New York, have invented certain new and useful Improvements in Devices for Computing the Cost of Engravings, of which the following is a specification.

This invention relates to squares and has 10 for its object to provide one in which are means for enabling the cost of photo-engravings, cuts, etc., to be computed by simpler calculations than heretofore have been necessary.

15 It has for a further object the provision of a square in which one arm is so constructed that slides bearing different price rates thereon may be used therewith.

With these objects in view, the invention 20 is as represented in the drawing, in which—

Figure 1 is a plan view of the square with one slide in place; Fig. 2 is an elevation of the slide showing the face opposite to that shown in Fig. 1; and Fig. 3 is a transverse 25 vertical section on line III—III of Fig. 1.

As shown, the square has two arms 1, 2, 30 at right angles to each other, and preferably held together at adjacent ends by metal plates *p*, the arm 1 being pivoted between

the plates *p* upon a pin 6. By such a construction, the square may be compactly folded, as indicated by dotted lines in Fig. 1. The arm 1 has two scales *a*, *b*, thereon, scale 35 *a* being an ordinary scale divided into inches and eighths, quarters, etc., while scale *b* is divided into inches and tenths of an inch.

The arm 2 is provided centrally with a longitudinally extending groove 3, which is so cut as to form flange portions 3', 3'' in said 40 arm. A price-rate slide 4, of substantially the same shape as groove 3, is inserted in the groove between the flange portions 3', 3'', the latter acting as guiding members for the slide 4. The top of both the flange portions 45 3', 3'' are preferably graduated in inches and tenths of an inch. The graduations on the right-hand flange portion 3'', however, are continued inwardly to the edge of the groove 3. In the center of slide 4 there are

50 graduations 5 every tenth of an inch, which are in alinement with those on the right-hand flange portion 3'' when the slide is in the proper position, as shown in Fig. 1. On

both sides of the graduations 5 are figures 55 which denote the price of an engraving at the particular rate used, having a length

equal to that indicated on the scale of the flange portion 3'' opposite the particular price graduation, and of unit width. In Fig. 1, the rate scales shown are for 20 and 18 60 cents per unit length and breadth. The reverse side of the slide 4 may be provided with different rate scales, as shown in Fig. 2, where the rates are 14 and 6 cents, respectively. These four rates on the scale ordinarily cover one entire field, comprising, for instance, line-cuts, half-tone squares, half-tone silhouettes, and combination half-tones, unless more than one rate on a particular engraving would be needed, when, of course, 65 extra slides with various price-scales could be provided. At its outer end the slide 4 extends slightly beyond arm 2, which enables one to grip the same. 70

Obviously the price rate figures may be 75 placed upon the arm of the square itself, where the idea of having replaceable scales is not desired.

When the square is closed (it is compact and saves space), one side can be used as a 80 regular ruler and the other side as a tenths ruler. It is not only a rapid calculator, but on proofs of engravings that are silhouetted this ruler at once forms a right-angle and gives a basis to work upon. 85

To use the square, arm 1 is extended, and the slide, having thereon the particular price rate, is inserted in the groove 3 as far as it will go, with the price-scale on top, when the graduations thereon will be in 90 alinement with those on the flange 3''. The print, cut, etc., to be measured is placed with its edges along the inner edges of the scale. To compute the cost of the engraving, its length in units and fractions thereof and 95 the price on the selected scale opposite this graduation are noted, and the latter multiplied by the number of units of width as noted on scale *b*. As for example, if it were required to find the cost of an engraving 7.4 inches wide by 6.3 inches long, at a rate of .18 dollar per square inch, the old method would require the multiplication of 7.4×6.3×.18. By the use of the present invention, the scale at once indicates that 100 for a length of 6.3, the rate at .18 is 1.134, which when multiplied by 7.4, the width, at once gives the cost as \$8.39.

I claim:—

1. In a device for computing costs depending upon the areas of rectangular figures, a square having on its arms gradu-

tions representing units of length, one of said arms having figures thereon opposite each graduation, each figure representing the cost for an area of a figure of a length indicated opposite such graduations on said arm, and of unit breadth.

2. In a device for computing costs depending upon the areas of rectangular figures, a square having its arms graduated in 10 units of length, a replaceable price-scale slide on one arm of said square, said price-scale slide having graduations thereon in alinement with those on the square.

3. In a device for computing costs depending upon the areas of rectangular figures, a square having its arms graduated in units of length, a replaceable price-scale slide on one arm of said square, said price-scale slide having graduations thereon in 20 alinement with those on the square and figures opposite each graduation, each figure representing the cost for an area of a figure of a length indicated opposite such graduation on the scale on said arm, and of unit 25 breadth.

4. In a device for computing costs depending upon the areas of rectangular figures, a square having its arms graduated in units of length, flange portions on the upper side of one of said arms, and a replaceable price-scale slide adapted to be inserted 30

in the arm of the square between said flange portions.

5. In a device for computing costs depending upon the areas of rectangular figures, a square having its arms graduated in 35 units of length, flange portions on the upper side of one of said arms, a replaceable price-scale slide inserted in the arm of the square between said flange portions, said price-scale slide having graduations thereon in alinement with those on the square.

6. In a device for computing the costs for 40 engravings, a square having its arms graduated in units of length, flange portions on 45 the upper side of one of said arms, bearing the graduations for that arm, a replaceable price-scale slide inserted in said arm between said flange portions, said price-scale slide having graduations thereon in alinement with those on the flange portions, and figures opposite the graduation, each figure representing the cost for an area of engraving of a length indicated opposite such 50 graduation on the scale on the flange portions, and of unit breadth.

In testimony whereof I affix my signature in presence of two witnesses.

EDWARD I. KRAMER.
